UNITED STATES PATENT OFFICE.

ALBERT C. BELL, OF CHICAGO, ILLINOIS, ASSIGNOR TO ADOLPH KRETZ AND ULRICH KORNSTEIN, BOTH OF CHICAGO, ILLINOIS.

TUBULAR LOCK.

1,228,172.

Specification of Letters Patent. Patented May 29, 1917.

Application filed July 10, 1916. Serial No. 108,285.

To all whom it may concern:

Be it known that I, ALBERT C. BELL, a citizen of the United States, residing at Chicago, in the county of Cook and State 5 of Illinois, have invented a certain new and useful Improvement in Tubular Locks, of which the following is a specification.

My invention relates to an improved form of tubular lock of simple construction, 10 which, however, is none the less effective since it may readily be made extremely difficult to pick. In my invention, the casing of the lock is in the form of a circular tube, all of the parts being preferably located 15 within the outer surface of the tube, so that the only operation required to receive the lock casing in the door or other article to be fastened by said lock is to bore a hole of substantially the outside diameter of the 20 casing.

My invention may be given a variety of embodiments as best illustrated in the drawings, in which—

Figure 1 is a longitudinal central sectional view through one form of lock construction,

Fig. 2 shows in side elevation a portion of the lock casing shown in Fig. 1,

Fig. 3 is an end elevation from the left 30 hand of the lock shown in Fig. 1,

Fig. 4 shows the form of key for use with the construction shown in Fig. 1,

Figs. 5 and 6 show in views similar to Fig. 1 other forms of lock construction, the 35 construction shown in Fig. 6 being the preferred form,

Fig. 7 shows in side view the casing for either of the constructions shown in Figs. 5 and 6,

Fig. 8 is an end view of the casing taken 40 from the right hand in Fig. 7,

Fig. 9 shows in side elevation the bolt construction employed in the construction of lock shown in Fig. 5,

Fig. 10 is a sectional view of the bolt 45 shown in Fig. 9 taken along the line 13—13,

Fig. 11 shows in a view similar to Fig. 1 a portion of a lock casing of modified construction in which the springs are formed 50 integrally with the wall of the casing and,

Fig. 12 shows in top view a modified form of spring construction which may be employed with several of the different lock constructions.

Similar numerals refer to similar parts 55 throughout the several views.

As shown in Figs. 1, 2 and 3, the lock consists of the metal tube 20 having tongues 21 projecting from its left hand end and entering notches formed therefor in the plate 22, 60 by means of which the tube 20 is secured to said plate preferably by riveting over the ends of the tongues 21. The plate 22 has formed therethrough co-axially with the tube 20 a hole of substantially the same size 65 as the bore of the tube 20 so that the bolt 23 may readily pass through the said hole when the lock is operated. The bolt 23 is preferably given the conformation indicated by means of suitable dies and is rigidly secured upon the left hand end of a tube 24 which extends nearly to the right hand end 70 of the casing 20. The casing 20 has formed in its upper portion a long slot 25 into which the spring 26 may enter when operated by the key 27 shown in Fig. 4. The wall of the casing near the observer is provided with a slot 28, as indicated in Fig. 2, 75 to receive the key 27, and the opposite wall of the tube casing is provided with a hole 29 80 to support the end of the key, there being clearance slots 30 formed in either side of the tube 24 to permit longitudinal motion of said tube relatively to said key. The lower portion of the tube 24 is provided 85 with a clearance slot 31 and the upper portion of said tube is provided with two adjoining slots 32 through which the operating portion of the key may pass to engage the spring 26 so as to raise the bent end 33 90 of said spring from engagement with the slot 34 formed in the upper portion of the tube in which said bent end may rest. The spring 26 is provided with a projecting bent portion 35 resting in the end of the slot 24 95 and continues inside of the casing 20 to its right hand end where it extends across the casing and inside the opposite side of the casing and terminates in a bent end 36 resting in a slot formed therefor in the wall of 100 the casing 20. The spring 26 therefore serves to support the right hand end of the tube 24 and, by the conformation of the spring described, it is prevented from moving longitudinally in the casing 20 when the tube 24 is in place therein.

When the lock is operated, the key, in turning, first enters one of the slots 32 and

raises the spring 26 so as to disengage the bent end 33 from the tube 34, after which continued motion of the key engages the end of the slot 32 and moves the tube 24 5 and bolt 23 longitudinally in the lock casing a sufficient distance so that the spring 26 engages the next one of the slots 34. If desired, a second slot 32 may be provided so that to completely throw the bolt of the lock 10 either to its locking or unlocking position a second rotation of the key is required. It will be observed, as a result of the construction of the parts that the outward motion of the spring 26 does not cause the spring to 15 pass outside of the outer circumference of the casing 20 and therefore, in mounting the lock in place in the door or other part to be secured by said lock, it is only necessary to bore a hole of substantially the diameter of 20 the outside of the casing in order that the lock may be inserted in place, and there is no danger of the parts binding or operating imperfectly since they do not in any case 25 project outside of the outer cylindrical surface of the casing.

In the construction shown in Fig. 5, the tubular casing 60 is provided with upper and lower longitudinal slots 61 and 62 respectively for receiving the ends of the 30 spring 63, each end of this spring being similarly formed to the upper portion of the spring 26 shown in Fig. 1 and having a bent end for the same purpose as referred to for the bent end 33 of the spring 26. In 35 this construction, however, the spring 63 extends over the casing and outside of the end thereof to connect the end portions of the spring together and the casing under the spring is flattened slightly as indicated 40 in Figs. 7 and 8, so that the spring may be wholly contained within the outer circumference of the tubular casing 60. The bolt in this case consists of a tube 64 loosely fitting the bore of the casing 60 and closed 45 at its left hand end by a plug 65. The bolt 64 is provided with operating, clearance and locking slots substantially the same as those illustrated for the tube 24 in Fig. 1, the only difference being that locking slots 50 are provided in both the upper and lower portions of the bolt. In this construction, the portions of the bolt engaged by the spring 63 are flattened as indicated more clearly in Figs. 9 and 10 to afford clearance 55 for the ends of the spring so that when the spring is operated it may not project through the slots 61 and 62 beyond the outer surface of the casing.

In the construction shown in Fig. 6, the 60 casing 65' is substantially the same as the casing 60 shown in Fig. 5 and the spring 66 is substantially the same as the spring 63 and operates in the same manner, the principal difference being that in this construction the bolt is formed from sheet metal by

suitable dies as indicated at 67 and is rigidly secured upon the left hand end of the tube 68 which is of circular cross section from end to end and carries the clearance and locking slots in substantially the manner 70 shown and described in connection with Fig. 5. This construction is the preferred embodiment of my invention, although I do not limit myself to this construction in carrying out my invention but may use any of the 75 other modified forms.

If desired, the casing of the lock for any of the constructions described may have the springs formed integrally therewith as indicated in Fig. 11 in which the springs 70 80 and 71 are formed from the upper and lower walls of the casing respectively by means of suitable dies. This construction is not, however, as satisfactory as when the spring is separately formed, for the reason that the 85 material of the lock casing to be easily worked by the forming dies is too soft to give the proper spring tension.

If desired each engaging end of the locking spring may consist of two parts as indicated in Fig. 12 at 73, so that each operating portion of the key may have two distinct operating surfaces, each formed to meet the requirements of the corresponding portion of the end of the locking spring and 90 the bent ends of these portions may project different amounts if desired, giving a basis for changing the shape of the key required to operate the lock, so that each style of lock may have a number of different keys 100 each capable of operating but a single one of the locks.

As a result of the construction described, it will be observed that by my invention, I provide a lock which is both cheap to make 105 and extremely efficient for the reason that, before the lock can be picked it is necessary to simultaneously remove all of the locking portions of the spring from engagement with the bolt and move the bolt longitudinally in the casing. My lock is applicable, therefore, to a wide variety of uses, such as doors for houses, for furniture, and in fact for any purpose except where the very highest grade of protection is required.

While I have shown my invention in the particular embodiments above described, I do not however limit myself to this construction, as I may employ equivalents thereof known to the art at the time of the filing of 110 this application without departing from the scope of the appended claims.

What I claim is:

1. In a lock construction, the combination of a tubular casing, a tubular bolt in the 125 casing having a portion of smaller diameter than the internal diameter of the casing, said bolt having an enlarged head at one end of substantially the inner diameter of the casing, and a spring carried by the casing hav- 130

5 ing its locking end within the inner surface of the casing and resting upon the smaller diameter portion of said bolt to in part guide said bolt, said spring having a bent end and said bolt having openings therethrough coöperating with said bent end for holding said bolt in its locking and unlocking positions, said bolt having openings therethrough for permitting the insertion 10 and turning of a key to disengage said spring from said bolt and move said bolt in said casing.

15 2. In a lock construction, the combination of a tubular casing, a tubular bolt in the casing having a portion of smaller diameter than the internal diameter of the casing, said bolt having an enlarged head at one end of substantially the inner diameter of the casing, and a spring carried by the casing 20 having its locking end within the inner surface of the casing and resting upon the smaller diameter portion of said bolt to in part guide said bolt, said spring having a bent end and said bolt having openings therethrough coöperating with said bent end for holding said bolt in its locking and unlocking positions, said bolt having openings 25 therethrough for permitting the insertion and turning of a key to disengage said spring from said bolt and move said bolt in said casing, said spring being separate from said casing and having bent projections holding it in place in said casing.

3. In a lock construction, the combination of a tubular casing, a tubular bolt in the casing having a portion of smaller diameter than the internal diameter of the casing, said bolt having an enlarged head at one 40 end of substantially the inner diameter of the casing, and a spring carried by the casing having its locking end within the inner surface of the casing and resting upon the smaller diameter portion of said bolt to in 45 part guide said bolt, said spring having a bent end and said bolt having openings therethrough coöperating with said bent end for holding said bolt in its locking and unlocking positions, said bolt having openings 50 therethrough for permitting the insertion and turning of a key to disengage said spring from said bolt and move said bolt in said casing, said spring being separate from said casing and having bent projections 55 holding it in place in said casing.

In witness whereof, I hereunto subscribe my name this 7th day of July, A. D. 1916.

ALBERT C. BELL.
